DISPENSING CLOSURE

Robert E. Hazard, North Kingstown, R.I., assignor to
Polytop Corporation, Slatersville, R.I., a corporation
of Massachusetts

Filed July 24, 1968, Ser. No. 12,885

Term of patent 14 years

Int. Cl. D9—02

U.S. Cl. D9—275

FIG. 1.

FIG. 2.

FIG. 3.

FIG. 4.

FIG. 5.

FIG. 6.

FIG. 1 is an isometric view of a dispensing closure embodying my new design;

FIG. 2 is an isometric view with the spout in open position;

FIG. 3 is a top plan view with the spout in closed position;

FIG. 4 is a front elevational view thereof;

FIG. 5 is a side elevational view; and

FIG. 6 is an isometric view showing a modified form of my new design.

The front and side elevational views of the dispensing closure shown in FIG. 6 are the same as the respective views of the dispensing closure of FIGS. 1 through 5.

The essential features of my new design resides in the appearance of the top of the dispensing closure.

I claim:

The ornamental design for a dispensing closure, as shown and described.
